UNITED STATES PATENT OFFICE.

CHARLES SWINSCOE, OF CLINTON, MASSACHUSETTS, ASSIGNOR TO THE CLINTON WIRE CLOTH COMPANY, OF SAME PLACE.

METALLIC LATHING.

SPECIFICATION forming part of Letters Patent No. 358,503, dated March 1, 1867.

Application filed September 8, 1866. Serial No. 212,979. (No model.)

To all whom it may concern:

Be it known that I, CHARLES SWINSCOE, of Clinton, in the county of Worcester, State of Massachusetts, have invented a certain new and useful Improvement in Metallic Lathing, of which the following is a description sufficiently full, clear, and exact to enable any person skilled in the art or science to which said invention appertains to make and use the same, reference being had to the accompanying drawings, forming part of this specification, in which—

Figure 1 is a plan view representing a piece or web of my improved metallic lathing, and Figs. 2 and 3 like views showing modifications of the improvement.

Like letters of reference indicate corresponding parts in the different figures of the drawings.

My invention relates to that class of metallic lathing which is composed wholly or in part of wire-cloth; and it consists in certain novel details of construction, as hereinafter fully set forth and claimed, the object being to produce a more effective and otherwise desirable article of this character than is now in ordinary use.

The nature of the improvement will be readily understood by all conversant with such matters from the following explanation.

In the drawings, A represents the web of cloth considered as a whole, B the warp-wires, and C the filling-wires. Disposed at intervals in the web A there are narrow flat metallic strips D, provided with a series of holes, x. These strips are interwoven with and held in position by the warp-wires B or filling-wires C, as the case may be, but preferably by the warp, and respectively take the places of one or more filling or warp wires, being inserted in the web as it is woven. The object of the strips is to sustain the web and keep it

in proper position when it is attached to the furring, and to afford a ready means of attaching it without the use of staples, ordinary 45 nails being employed for this purpose, which are driven through the holes x. The strips may be provided with holes for the nails, as shown in Fig. 1, or made without holes, as shown in Fig. 2, or every alternate strip may 50 be provided with holes, as shown in Fig. 3. When not provided with holes, the holes may be formed by any suitable implement as the lathing is put up, and when the strips are thin enough to permit it the nails may be 55 driven through them into the furring or beams without first punching holes therefor. It is preferable, however, to provide the strips with nail-holes, and to have them sufficiently rigid to sustain the web without sagging when the 60 plastering is applied. It is also preferable to insert the strips in the filling; but they may be inserted in the warp. To impart additional rigidity or strength to the strips, they may be corrugated longitudinally, if desired. 65

Having thus explained my invention, what I claim is—

1. A plain uncorrugated web or piece of wire lathing comprising interwoven warp and filling wires, said web being provided at intervals with flat metallic strips interwoven with the wires and adapted to receive fastening-nails, substantially as described.

2. A web or piece of wire lathing comprising interwoven warp and filling wires, said web being provided at intervals with flat metallic strips interwoven with the wires, said strips being provided with nail-holes, substantially as described.

CHARLES SWINSCOE.
